UNITED STATES PATENT OFFICE.

HAROLD EUGENE TREWORGY, OF BRUNSWICK, MAINE.

KINDLER HOLDER FOR WICKS.

Application filed February 17, 1927. Serial No. 168,989.

This invention relates to improvements in kindler holders for wicks, particularly in a kindler made of any suitable non-inflammable material, preferably metal.

- 5 An object of this invention is to provide a kindler holder which will function to allow the wick to be easily removed when desired, after the wick has been consumed to the ordinary extent.
- 10 Another object of this invention is to provide a device which will eliminate to some extent the objectionable features of substances which boil over from passing down around the wick, thereby increasing the life and efficiency of the heating device.

15 Other objects of this invention will appear from the following detailed description of the device and as disclosed in the single sheet of drawings which is herewith made a part of this application.

In the drawings—

Figure 1 illustrates a perspective view of the kindler holder for a wick disclosing the wick and holder in assembled relationship.

25 Figure 2 represents a vertical sectional view of the kindler holder showing the laterally extending flange portion.

30 Figure 3 illustrates a perspective view of a modification of Figure 1 disclosing the kindler holder at the inside periphery of the wick instead of the outside as disclosed in Figure 1.

Figure 4 represents a vertical sectional view of the kindler holder disclosed in Figure 3.

35 Numeral 1 designates a kindler holder made of any suitable non-inflammable material adapted to carry or hold a wick 2 in position in cooperation with a resilient or bendable lug portion 3, preferably integrally connected to the body portion 1 of the kindler holder, and extending at intervals along the lower periphery of the holder 1.

In order to provide an easy means for removing the wick when it has reached the useful consumed stage, a laterally extending flange portion 4 is formed along the upper periphery of the kindler holder 1 either extending outwardly from the holder 1 as disclosed in Figure 1, or extending inwardly as disclosed at 5 in Figure 3, wherein nu-

meral 6 designates a kindler holder disclosing a modification of this invention, in that the holder is adapted to be located along the inner periphery of the wick instead of the outer periphery as disclosed in Figure 1.

It is to be understood that the kindler holder may be perforated as disclosed at 7 in Figure 2.

The laterally extending flange portions 4 60 and 5 may be completely circumferential of the kindler holder or intermittent without affecting the merits of this invention.

In operation this invention provides a kindler holder for a wick which will function to allow the easy removal of a wick when desired from an oil stove or other suitable type of heating device, thereby eliminating one of the chief disadvantages in the use of oil stoves particularly.

70 Another object of this invention is to prevent, to some extent, substances which boil over, while the stove is in use, from passing down around the wick, thereby greatly increasing the life and efficiency of the wick or kindler holder.

75 It has always been difficult to remove wicks or kindlers after having been long in use, thereby limiting materially the sale of oil stoves.

80 This invention provides a means for overcoming the above disadvantages.

85 It is understood that substitutions and alterations may be made in the disclosure as above set forth within the scope of the claims without in any manner affecting the merits of this invention.

What I claim is:—

1. The combination with a heating device, of a kindler holder, of a wick held in position by the kindler holder, of means for easily removing the kindler holder and wick from the heating device, consisting of a flange portion extending laterally of the holder, means for maintaining the wick in operative relationship with the holder, consisting of lug portions integrally a part of the holder and bent inwardly and upwardly thereof.

100 2. The combination with a heating device, of a kindler holder, of a wick held in position by the kindler holder, of means for easi-

ly removing the kindler holder and wick from the heating device, consisting of a flange portion extending laterally of the holder, means for maintaining the wick in operative relationship with the holder, consisting of lug portions integrally a part of the holder and bent inwardly and upwardly

thereof, the inwardly and upwardly extending lug portions being located at suitable intervals around the lower periphery of the 10 holder.

In testimony whereof I affix my signature.

HAROLD EUGENE TREWORGY.
